Richmond & Caswell, Jr.

Making Hoes and Shovels.

Patented Apr. 7, 1831.

N. PETERS, PHOTO-LITHOGRAPHER, WASHINGTON, D. C.

6460 X April 7, 1831²³²

to Charles Richmond & Samuel Baswell junr.
Letters Patent, dated April 7, 1831.

The Schedule referred to in the Letters Patent and making part of the same containing a description in the words of the said Charles Richmond & Samuel Baswell Junior themselves of their improvement, in the mode of manufacturing Spades and Shovels by means of machinery.

To all whom it may concern: Be it known that we Charles Richmond and Sam'l Baswell junr. have invented an improved mode of manufacturing Spades and Shovels by machinery; whereby much labor is saved and the articles manufactured are made with greater truth and uniformity than by the modes hitherto pursued; and that the following, is a full and exact description of our said invention.

The principal machinery which we employ is such as is well known to mechanists, and to this therefore we make no claim; as we have merely improved, in size and form, as to adapt it to the purpose to which we apply it.

That our mode of procedure may be perfectly understood, we have deposited in the Patent Office of the United States, drawings of the machinery, as modified and applied by us; and also a model of the same corresponding with the same.

This machinery consists first of a cutting "Press bed" upon which the plate prepared for making a Spade or shovel, is cut out at one operation; and by another operation is punched, to receive the rivets necessary to attach the back strap and coffin to the plate.

The second part of the machinery is a stamping apparatus, usually called a die. This has a bed, fire, or anvil which is fixed below the stamping die, and from

one part of the die by which the spade, or shovel is to be shaped, the lifting part of the tool is made to correspond to this and forms the upper part of the die.

To make a spade, or shovel we take a bar of Swedish, or other iron and upon the side of this we usually weld a piece of steel.

The bar is then rolled out to the size necessary for forming the spade or shovel. It is then placed under the cutting press, and is cut out at one operation.

The same press receives dies to cut the strap, and also to punch the requisite holes, each of which is also effected at one operation.

The plates, so cut, are then placed in the drop, and by a single blow, receive the form required.

The improvement, which we have made in the manufacture of Spades and Shovels and for which we claim a patent, is the use of cutters and dies, used in the cutting press and drop, by which the plate of which the spade, or shovel is to be made is first cut out and afterwards stamped into the proper shape, each by a single operation.
